UNITED STATES PATENT OFFICE.

GUSTAV STICKLEY, OF MORRIS PLAINS, NEW JERSEY.

DESIGN FOR AN ANDIRON.

42,653.

Specification for Design.

Patented June 18, 1912.

Application filed January 29, 1912. Serial No. 674,221. Term of patent 14 years.

To all whom it may concern:

Be it known that I, GUSTAV STICKLEY, a citizen of the United States, residing at Morris Plains, New Jersey, have invented and produced a new, original, and ornamental Design for Andirons, of which the following is a specification, reference being had to the accompanying drawings, in which—

The design comprises the upright standards —a—, pyramidal in form from bottom to top and terminating in a scroll at the upper end, and a rod extending longitudinally from, and attached to the upright —a— in the manner shown.

What I claim is:

The ornamental design for andirons as shown and described.

GUSTAV STICKLEY.
